UNITED STATES PATENT OFFICE

NORMAN L. SNOW, OF NEW CANAAN, CONNECTICUT, AND CURTIS L. HOWSE, OF DETROIT, MICHIGAN, ASSIGNORS TO DIAMOND POWER SPECIALTY CORPORATION, OF DETROIT, MICHIGAN, A CORPORATION OF MICHIGAN

BOILER CLEANER

Application filed October 12, 1925, Serial No. 62,102. Renewed July 27, 1931.

The invention relates to boiler cleaners and refers more particularly to an improved device for cleaning various parts of the boiler. A further feature of the invention resides in the provision of means for cooling the boiler cleaner.

Referring to the drawings in which like reference characters indicate corresponding parts:

10 Figure 1 is a plan view in cross section through a boiler water leg showing one embodiment of our boiler cleaner;

Figure 2 is a sectional view along 2—2 of Figure 1;

15 Figure 3 is a sectional view in elevation through a boiler water leg illustrating a further embodiment of our invention;

Figure 4 is a view along 4—4 of Figure 3;

20 Figure 5 is a view corresponding to Figure 2 illustrating a modified construction;

Figure 6 is an end elevation view of the blower shown in Figure 5;

Figure 7 is a view corresponding to Figure 5 illustrating a modified construction;

25 Figure 8 is a fragmentary sectional view of the discharge portion of a modified construction of boiler cleaner.

Referring to Figure 1 we have shown one form of a boiler cleaner wherein a cooling fluid such as air is caused to travel through the barrel or nozzle chambers of the blower which for purposes of illustration is shown as the non-retracting type. 10 is the exterior wall and 11 the interior wall of the water leg

30 12 of a boiler which, in the present instance is of the locomotive type. Into this water leg is expanded a nipple 13 and within the nipple lies the barrel 14 of the blower or boiler cleaner 15. Barrel 14 is mounted in the

35 housing 16 which is fixed to the exterior water leg wall by any suitable means such as the cap-screws 17. The nozzle head 18 is provided with a plurality of nozzles 9 of varying angularity for discharging jets of cleaning fluid

40 in varying directions toward the parts of the boiler to be cleaned such as the flue sheet 19 and the tubes 20. The nozzles 9 are adapted to be successively placed in connection with the steam or other cleaning fluid inlet 21 by

45 50 reason of the fixed port 22 of the barrel 14

and the passages 23. These passages extend longitudinally of the barrel and respectively communicate with the nozzles 9 and the inlet port 22 through the ports 24 of the passages. The rotation of the nozzle head 55 within the barrel 14 is accomplished by operation of a cable 25, the latter passing over the sheave wheel 26 fixed with operating rod 27. This latter rod is fixed as at 28 with the nozzle head 18.

60 During periods of non-blowing or non-operation of the blower when cooling is more particularly desired, the draft in the fire box pulls a cooling fluid such as air through the air inlet 29 to the chamber 30 and thence through a series of ports 31, these ports establishing a communication with the chamber 30 and the respective passages 23. However, when the cleaning fluid is turned on so as to enter one or more of the passages 23 communicating with the inlet port 22, the port 31 of such chambers will be automatically closed by reason of a ball valve 33, the pressure of the cleaning fluid forcing this valve to the left to close the port 31.

65 70 75 80 85 89 As soon as any passage 23 is rotated into non-communication with the inlet 22 or whenever the cleaning fluid is shut off, these ball valves will automatically assume the positions shown in Figure 1 whereby the cooling air will circulate freely through the ports 31, passages 23 and nozzles 9. Means is thus provided for efficiently cooling the boiler cleaner and automatically preventing the escape of cleaning fluid.

90 95 99 The air inlet 29 communicating with the chamber 30 may be fitted with a suitable extension 30a, the inlet end of which may be covered by a screen 31a for filtering any dirt, dust, or the like, from the incoming air.

An additional air passage 32 may be provided which, as shown in Figure 1, may extend axially through the rod 27 and the nozzle head 18. Such a passage affords additional cooling apart from the aforesaid cooling system including the air chamber 30.

In the event that it is not desired to admit air or other cooling fluid into the fire box when the blower is not operating, the blower may be cooled by passing air through some of

the nozzles and returning it to a point outside the fire box through other nozzles as shown in Figures 3 and 4. In these figures the air is shown circulating through the nozzle chambers 23 in the direction indicated by the arrows. The air enters the flared opening 33 which is turned in the direction of travel of the locomotive. An impelling force is thus imparted to the air which then passes through the elbow 34, duct 35, opening 36 and thence through the various ports 37 in communication with the opening 36. The air then travels longitudinally through the passages 23. Instead of being pulled into the fire box, as in Figure 1, the air is deflected by a cap 38 and the direction of travel of the air is thus reversed causing the same to flow through the nozzles 9 and the respective passages 23 which have their ports 37 in communication with the cleaning fluid inlet 21. From the passage 21 the air is conducted through the opening 39 of the air relief valve 40 and thence through elbow 41 to the flared opening or funnel 42 in communication with the atmosphere. The funnel 42 at the outlet end may be turned in a direction opposite to that of the funnel 33 at the inlet end whereby a suction force is secured at the outlet end and a pressure at the inlet end. By reversing the directions of these funnels the direction of flow of the air through the blower may be reversed causing the air to pass in a direction opposite to that indicated by the arrows. In the non-blowing position of the parts, the outer peripheral edge of the cap 38 is in contact with the inner wall 11 of the water leg 12, thus preventing passage of the cooling air into the fire box. In order to permit removal of the cap from the path of the jets issuing from the nozzles 9 when the cleaning fluid is turned into the system, the cap is fixed to a plunger 43. Extending axially of the blower is a spring 44 mounted on the end of this plunger for normally holding the cap in the position shown in Figure 3. When so held the cap closes communication of the nozzles with the fire box thus compelling the air entering from one set of nozzles to pass out through another set. The relative circumferential lengths of the passages 36 and 21 will determine the number of nozzles open on the air inlet and air outlet sides respectively. When the steam is turned into the system, the valve disc 40 is pushed against its seat by the steam pressure against the action of the spring 45. This closes the air relief valve passage 39, while the steam is turned on and prevents the escape of steam through the valve. The steam also enters a chamber 46 through passage 47 and thence passes through ports 48 to the chamber 49 where it acts to push the plunger 43 outward against the action of spring 44. The cap 38 is thus pushed outwardly beyond the nozzles thus permitting the steam from the nozzles to blow in the di-

rection of the locomotive flue sheets. Rotation of the nozzle head may be obtained by an operating shaft 50 and the bevel gears 51 and 52, the latter being fixed with the nozzle head or body 18.

The cap 38 and plunger 43 may be formed of a suitable heat-resisting metal, thus protecting the nozzle head from the scrubbing action of the gases and the radiant heat of the fire box.

Referring to Figures 5 and 6 we have shown a blower of the same general construction as described in the figures referred to above, this blower being provided with a plate or cap 53 of a heat-resisting metal. This plate is open only for the area as shown at 54 in Figure 6, sufficient to permit the discharge of steam from the nozzles receiving steam from the supply 21 for projecting the jets toward the flue sheet 19. This plate 53 comprises the protecting and deflecting plate as shown in Figure 6, this plate being formed integrally with the longitudinally extending cylindrical portion 55 lying between the nozzle barrel and nipple 13. The end of the portion 55 may be bent over at 56 and held to the blower casing by means of a lug 57 secured to the casing by fasteners 58.

In this construction cooling air may enter the duct 36, flow through the passages 23, and be returned to the atmosphere through the axially extending passageway 32'.

The apparatus may also be cooled by conduction to the water in the water leg 12 of the boiler. As illustrated in Figure 5, the casing 55 may be made a driving fit in the sleeve of nipple 13 which is expanded into the water leg. By reason of this close fit heat absorbed by the casing is in turn, readily transmitted to the water in the water leg of the boiler.

If desired, the nipple expanded in the water leg of the boiler as shown in Figure 5 for example, may be dispensed with by a construction such as shown in Figure 7. In this figure the casing 14' is threaded at the points 59 and 60 to engage suitable threads in the walls 11 and 10 respectively of the water leg 12. The opening in the wall 10 may be made larger than that in the wall 11 so that the blower may be readily inserted and threaded into both walls simultaneously. By reason of this construction the nozzle head or barrel portion 18 is separated from the water in the water leg 12 only by the casing 14' so that the heat will be effectively dissipated.

In the event that very high temperatures are encountered the blower casing proper may readily be built of a material having a low heat resistance such as steel, so as to constitute a good heat conductor for example, while the nozzle chamber may be constructed of a material having a relatively high heat resistance and therefore of poor heat conductivity since

the nozzle chamber is exposed to more direct heat from the fire box.

Referring to Figure 8 the head 18 is so constructed that it may be positioned into close contact with one of the walls of the water leg 11 whereby the nozzles and nozzle head are cooled. The portion of the nozzle head 61 lying between the wall 11 and the nozzles 9 may be of varying thickness to compensate for the varying angularity of the nozzles. The nozzle sections 62 may be formed of a cross section gradually increasing toward the body of the blower thus adding an increasing heat conduction toward these heavy sections. These latter sections which are housed within the water leg 12 may in turn be cooled by conduction to the water.

What we claim as our invention is:—

1. The combination with a boiler water leg, of a boiler cleaner mounted in said water leg and provided with nozzles adapted to discharge cleaning fluid toward parts of the boiler to be cleaned, said cleaner having cleaning fluid conducting passages, and means for introducing a cooling fluid into certain of said passages during the operation of the cleaner.

2. A boiler cleaner comprising a housing provided with an inlet port, a body rotatable within the housing and provided with a plurality of passages adapted to successively communicate with said inlet port, upon the rotation of said body, nozzles for discharging the cleaning fluid from said passages respectively, and means for causing a circulation of cooling air through some of said passages during operation of said cleaner.

3. A boiler cleaner comprising a housing provided with an inlet port, a body rotatable within the housing and provided with a plurality of passages adapted to successively communicate with said inlet port, upon the rotation of said body, nozzles for discharging the cleaning fluid from said passages respectively, means for causing a circulation of cooling air through said passages, and means automatically controlled by a supply of cleaning fluid toward said boiler cleaner nozzles for shutting off the circulation of cooling air to each passage as the cleaning fluid enters each respective passage.

4. A boiler cleaner comprising a housing provided with an inlet port, a body rotatable within the housing and provided with a plurality of passages adapted to successively communicate with said inlet port, upon the rotation of said body, nozzles for discharging the cleaning fluid from said passages respectively, and valve controlled means for causing a circulation of cooling air through some of said passages during operation of said cleaner.

5. A boiler cleaner comprising a housing provided with an inlet port, a body rotatable within the housing and provided with a plurality of passages adapted to successively

communicate with said inlet port, upon the rotation of said body, nozzles for discharging the cleaning fluid from said passages respectively, and means for causing a circulation of a cooling fluid through passages whose ports are not in registry with the said inlet port and for automatically shutting off the circulation of the cooling fluid through the passages whose ports are in registry with said inlet port.

6. A boiler cleaner extending transversely of a boiler wall and provided with a cleaning fluid discharge nozzle, and means for circulating a cooling fluid through the boiler cleaner, said means including said nozzle, and inlet and outlet cooling fluid ports located outside and on the same side of the said boiler wall.

7. A boiler cleaner extending transversely of a boiler wall and provided with a cleaning fluid discharge nozzle, and means for circulating a cooling fluid through the boiler cleaner and transversely of the boiler wall, said means including said nozzle, and inlet and outlet cooling fluid ports located outside of the said boiler wall.

8. A boiler cleaner extending transversely of a boiler wall and provided with a cleaning fluid discharge nozzle, and means for circulating a cooling fluid through the boiler cleaner, said means including said discharge nozzle and normally open inlet and outlet cooling fluid ports located outside of the said boiler wall, and a valve adapted to close one of said ports when the cleaning fluid is being discharged from said nozzle.

9. A boiler cleaner extending transversely of a boiler wall and provided with a cleaning fluid discharge nozzle, means for circulating a cooling fluid through the boiler cleaner, and a cap positioned adjacent the said nozzle and movable away from said nozzle under the influence of the cleaning fluid, said cap forming a part of the cooling fluid circulating means and preventing the cooling fluid from escaping from the nozzle into the combustion chamber, when located in its retracted position adjacent the nozzle.

10. A boiler cleaner extending transversely of a boiler wall and provided with a cleaning fluid supply pipe, a nozzle adapted to discharge the cleaning fluid from said supply pipe adjacent parts of the boiler to be cleaned, a cap positioned adjacent the nozzle for protecting the same from the gases and heat of the combustion chamber, and a member mounting said cap and extending transversely of said wall.

11. A boiler cleaner extending transversely of a boiler wall and provided with a cleaning fluid supply pipe, a nozzle adapted to discharge the cleaning fluid from said supply pipe adjacent parts of the boiler to be cleaned, a cap positioned adjacent the nozzle for protecting the same from the gases and heat of the combustion chamber, a plunger rigidly

associated with the cap extending axially through said boiler cleaner and transversely through said boiler wall, said cap and plunger being formed of a heat resisting material.

- 5 12. A boiler cleaner extending transversely of a boiler wall and provided with a cleaning fluid supply pipe, a nozzle adapted to discharge the cleaning fluid from said supply pipe adjacent parts of the boiler to be cleaned, a cap positioned adjacent the discharge end of the boiler cleaner for protecting the discharge nozzle from the heat of the combustion chamber, and means for circulating cooling air from a point without the boiler wall longitudinally of the boiler cleaner and transversely between the said cap and the adjacent end of the boiler cleaner.

10 13. The combination with a locomotive boiler water leg, of a boiler cleaner mounted in said water leg and provided with a nozzle adapted to discharge cleaning fluid toward parts of the boiler to be cleaned, said cleaner having a cleaning fluid conducting passage, and means for introducing air into said passage, said means including a member open to the atmosphere and facing in the direction of travel of the locomotive, thereby inducing a flow of air through said member and into said passage when the locomotive is in motion.

15 14. The combination with a boiler, provided with a combustion chamber, of a blower extending through the wall of said boiler from the exterior thereof and provided with a nozzle arranged to discharge cleaning fluid against a heat transfer surface in said chamber, a cap disposed within said chamber and normally positioned over said nozzle to protect the same from the heat of the chamber and movable from said position to permit unobstructed discharge from said nozzle, an inlet port and an outlet port for a cooling medium arranged at the outside of the boiler and conduit means connecting said ports, said

20 45 conduit means being defined in part by said cap when in normal position.

25 15. The combination with a boiler provided with a combustion chamber, of a blower extending through the wall of said boiler from the exterior thereof and provided with a nozzle arranged to discharge cleaning fluid against a heat transfer surface in said chamber, a cap disposed within said chamber and normally positioned over and spaced from said nozzle to form a passage between the end of said nozzle and said cap and to protect the nozzle from the heat of the chamber, said nozzle being movable from said position to permit unobstructed discharge from said nozzle, an inlet port and an outlet port for a cooling medium arranged at the outside of the boiler and conduit means connecting said ports, said conduit means being defined in part by said cap when in normal position.

30 16. The combination with a boiler provided

with a combustion chamber, of a blower extending through the wall of said boiler from the exterior thereof and provided with a nozzle arranged to discharge cleaning fluid against a heat transfer surface in said chamber, a cleaning fluid supply pipe for said blower, a cap disposed within said chamber and normally positioned over said nozzle to protect the same from the heat of the chamber, and movable from said position to permit unobstructed discharge from said nozzle, a port in said supply pipe, a valve controlling said port, and means affording a circulation of a cooling fluid during periods of non-blowing from a point on the exterior of the boiler wall through said boiler cleaner to a point adjacent the said cap and thence through said port, said valve being adapted to be seated by the cleaning fluid in the said supply pipe.

35 17. The combination with a boiler provided with a combustion chamber, of a blower extending through the wall of said boiler from the exterior thereof and provided with a nozzle arranged to discharge cleaning fluid against a heat transfer surface in said chamber, a cleaning fluid supply pipe for said blower, a cap disposed within said chamber and normally positioned over said nozzle to protect the same from the heat of the chamber, and movable from said position to permit unobstructed discharge from said nozzle, a port in said supply pipe, a valve controlling said port, means affording a circulation of a cooling fluid during periods of non-blowing from a point on the exterior of the boiler wall through said boiler cleaner to a point adjacent the said cap and thence through said port, said valve being adapted to be seated by the cleaning fluid in the said supply pipe, and means actuated by the cleaning fluid for moving said cap to clear the discharge nozzle during blowing periods.

40 18. The combination with a blower element having cleaning fluid discharge passages, of means for flowing a cooling fluid in a tortuous path through said passages.

45 19. The combination with a blower element having a plurality of longitudinally extending cleaning fluid discharge passages, of means for flowing a cooling fluid from one end of said element through one of said passages to the opposite end of the element and back through said element through another of the said passages.

50 20. The combination with a blower element having cleaning fluid discharge passages and cleaning fluid discharge nozzles communicating with said passages, of means for flowing a cooling fluid in a tortuous path through said passages and through said nozzles.

55 21. The combination with a blower element having cleaning fluid discharge passages and cleaning fluid discharge nozzles communicating with said passages, of means normally

forming a fluid conducting passage connecting said nozzles, and means for flowing a cooling fluid through the said blower element and from one of the said nozzles to another 5 of the same.

22. The combination with a blower element having cleaning fluid discharge passages and cleaning fluid discharge nozzles communicating with said passages, of a cap normally 10 forming with the end of said element a fluid conducting passage connecting the said nozzles, and means for flowing a cooling fluid through the said element and through the fluid conducting passage formed by the cap 15 to cause the said cooling fluid to circulate from one nozzle to another.

23. In a boiler cleaner, a blower element, means for supplying a cleaning fluid to said blower element inlet and outlet ports for permitting the circulation of a cooling fluid through said blower element, and a valve actuated by the pressure of the cleaning fluid for controlling said outlet port.

24. In a boiler cleaner, a blower element, 25 valve controlled means for supplying cleaning fluid to said element, inlet and outlet ports for permitting the circulation of a cooling fluid through said element during periods when the supply of cleaning fluid is cut off, 30 and means operable upon the supplying of cleaning fluid to said blower element for closing said outlet port.

25. In a boiler cleaner, a blower element, 35 inlet and outlet ports for permitting the circulation of a cooling fluid through said element, and a pressure-controlled valve for said outlet port.

26. In a boiler cleaner, a blower element, 40 a cleaning fluid supply pipe for said element, an inlet port for admitting a cooling fluid to said element to cool the same, an outlet port in said supply pipe for permitting the discharge of the cooling fluid from the said blower element, and a valve controlling said 45 outlet port.

27. In a boiler cleaner, a blower element, 50 a cleaning fluid supply pipe for said element, an inlet port for admitting a cooling fluid to said element to cool the same, an outlet port in said supply pipe for permitting the discharge of the cooling fluid from the said blower element, and a valve controlling said 55 outlet port, said valve being adapted to be closed by the pressure of the cleaning fluid when cleaning fluid is supplied to said element through said supply pipe.

28. A boiler cleaner, including a source of supply of cleaning fluid, a discharge nozzle, a cleaning fluid supply passage leading to said nozzle, means to pass a cooling fluid through said passage, and means to prevent escape of cooling fluid from said nozzle into the gas space of the boiler, said means being movable upon the supply of cleaning fluid to said passage to permit the discharge of clean-

ing fluid from said nozzle into said gas space of the boiler.

29. In a boiler cleaner, a blower element having a discharge nozzle for directing a jet of cleaning fluid into the gas space of the 70 boiler adjacent the portion of the boiler to be cleaned, means for supplying a cleaning fluid to said blower element, means for supplying a cooling fluid to said blower element, and means for preventing discharge of the cooling fluid from said blower element into the 75 gas space of the boiler, said means being operable upon the supplying of cleaning fluid to the blower element to permit the discharge of cleaning fluid through said nozzle adjacent the portion of the boiler to be cleaned.

30. In a boiler cleaner, a blower element having a cleaning fluid discharge nozzle arranged to direct a cleaning fluid into the gas space of the boiler adjacent portions of the 80 boiler to be cleaned, means for supplying a cleaning fluid to said blower element, means for passing a cooling fluid through said blower element, and a member located adjacent said discharge nozzle for preventing the escape 85 of the cooling fluid into the gas space of the boiler, said member being movable by the pressure of the cleaning fluid upon the supply of cleaning fluid to the blower element to permit discharge of the cleaning fluid from 90 said nozzle into the gas space of the boiler adjacent the portions of the boiler to be cleaned.

31. In a boiler cleaner, a discharge nozzle arranged to direct a jet of cleaning fluid into the gas space of the boiler adjacent a portion 100 of the boiler to be cleaned, a cleaning fluid supply passage leading to said nozzle, means for supplying a cleaning fluid to said passage, means for passing a cooling fluid through 105 said passage, and a member yieldably held in a position adjacent said discharge nozzle to prevent the discharge of cooling fluid from said nozzle into the gas space of the boiler, said member being movable by the pressure 110 of the cleaning fluid supplied to said discharge nozzle to a position permitting discharge of the cleaning fluid from said nozzle into the gas space of the boiler adjacent the portions of the boiler to be cleaned.

32. A boiler cleaner comprising a housing provided with an inlet port, a body rotatable within the housing and provided with a plurality of passages adapted to successively communicate with said inlet port upon rotation of said body, nozzles for discharging the cleaning fluid from said passages respectively, means for causing a circulation of cooling air through some of said passages, and means for causing a circulation of air axially 120 through said rotatable body.

33. A boiler cleaner extending transversely of a boiler wall and provided with a cleaning fluid supply pipe, a nozzle adapted to discharge the cleaning fluid from said sup- 130

ply pipe adjacent parts of the boiler to be cleaned, a cap positioned adjacent the discharge end of the boiler cleaner for protecting the discharge nozzle from the heat of the combustion chamber, said cap being provided with a portion extending longitudinally of the boiler cleaner and between the same and the said boiler wall.

34. The combination with a boiler wall having an opening extending transversely therethrough and a nipple secured within the said opening of a boiler cleaner having a body portion housed within the opening and provided with a discharge nozzle adapted to discharge a jet of cleaning fluid adjacent parts of the boiler to be cleaned, a cap extending transversely across the nozzle end of the boiler cleaner and provided with a sleeve extending substantially at right angles with the cap and lying between the nipple and the boiler cleaner body portion.

35. The combination with a boiler wall having an opening extending transversely therethrough and a nipple secured within the said opening, of a boiler cleaner having a body portion housed within the opening and provided with a discharge nozzle adapted to discharge a jet of cleaning fluid adjacent parts of the boiler to be cleaned, a member provided with a cap portion extending transversely across the nozzle end of the boiler cleaner and provided with a sleeve portion extending substantially at right angles with the cap portion and lying between the nipple and the boiler cleaner body portion, and means for circulating cooling air longitudinally through said body portion into contact therewith and said cap.

36. The combination with a boiler water leg having an opening extending transversely therethrough and a nipple secured within the said opening of a boiler cleaner having a body portion housed within the opening and provided with a discharge nozzle adapted to discharge a jet of cleaning fluid adjacent parts of the boiler to be cleaned, said nozzle having a portion lying in face contact with a wall of said water leg for cooling the nozzle.

37. The combination with a boiler water leg having an opening extending transversely therethrough and a nipple secured within the said opening of a boiler cleaner having a body portion housed within the opening and provided with a plurality of discharge nozzles adapted to discharge jets of cleaning fluid at varying angles relatively to each other toward parts of the boiler to be cleaned, said nozzles being positioned for thermal contact with the said water leg for cooling the nozzles.

38. The combination with a boiler water leg having an opening extending transversely therethrough and a nipple secured within the said opening of a boiler cleaner having a

body portion housed within the opening and provided with a plurality of discharge nozzles adapted to discharge jets of cleaning fluid at varying angles relatively to each other toward parts of the boiler to be cleaned, 70 said nozzles being positioned for thermal contact with the said water leg for cooling the nozzles, and means for imparting rotation to the said nozzles while in contact with the water leg as aforesaid.

39. The combination with a boiler wall having an opening extending transversely therethrough and a nipple secured within the said opening of a boiler cleaner having a body portion housed within the opening and provided with a discharge nozzle adapted to discharge a jet of cleaning fluid adjacent parts of the boiler to be cleaned, said nozzle being positioned for thermal contact with the water leg of the boiler, and having a wall 80 of increasing cross sectional thickness for facilitating heat conduction from the nozzle to the water within the said water leg.

40. The combination with a boiler wall having an opening extending transversely therethrough and a nipple secured within the said opening of a boiler cleaner having a body portion housed within the opening and provided with a plurality of discharge nozzles adapted to discharge jets of cleaning fluid at varying angles relatively to each other toward parts of the boiler to be cleaned, said nozzles being positioned in contact with the said water leg for cooling the nozzles, said nozzles having a portion of 85 increasing cross sectional thickness toward the said body portion for aiding in heat conduction from the nozzles to the water within the said water leg.

41. The combination with a blower element having cleaning fluid discharge passages, cleaning fluid discharge nozzles communicating with said passages, and an auxiliary fluid conducting passage, of means for flowing a cooling fluid through said 105 cleaning fluid discharge passages and to said auxiliary fluid conducting passage.

42. The combination with a blower element having a plurality of longitudinally extending cleaning fluid discharge passages 115 and an auxiliary longitudinally extending fluid conducting passage, of means for flowing a cooling fluid from one end of said element through one of said cleaning fluid discharge passages to the opposite end of the 120 element and back through said element by way of said auxiliary fluid conducting passage.

43. The combination with a blower element having cleaning fluid discharge passages, cleaning fluid nozzles communicating with said passages, and an auxiliary fluid conducting passage extending longitudinally through said blower element, of a cap forming with the end of said element a fluid con- 125 130

ducting passage connecting certain of said nozzles with said auxiliary fluid conducting passage, and means for flowing a cooling fluid through said element by way of one of said cleaning fluid discharge passages, and through the fluid conducting passage formed by the cap and back through said blower element by way of said auxiliary fluid conducting passage.

44. The combination with a rotatable blower element having a plurality of cleaning fluid discharge passages, an auxiliary fluid conducting passage, and means for supplying cleaning fluid successively to said cleaning fluid discharge passages upon rotation of said blower element, of means for effecting a circulation of cooling fluid through the remaining cleaning fluid discharge passages not supplied with cleaning fluid and through said auxiliary fluid conducting passage during the operation of the blower element.

In testimony whereof we affix our signatures.
